(57) **CLAIM**

The ornamental design for a microphone, as shown and described.

DESCRIPTION

FIG. 1 is a top, front, right perspective view of a microphone showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The uneven-length broken lines and the even-length broken lines immediately adjacent to the shaded area define the bounds of the claimed design and form no part thereof. The remaining even-length broken lines show portions of the microphone that form no part of the claimed design. The stippling of FIGS. 1-2 and 4-7 does not represent any particular color, pattern, material, texture, or finish.
